UNITED STATES PATENT OFFICE

MOSES SCHNEIDER, OF BAYONNE, NEW JERSEY

CLOTH UNROLLING DEVICE

Application filed August 10, 1929. Serial No. 384,993.

My invention relates to devices for rolling and unrolling bolts of cloth and is designed particularly for use by manufacturers of clothing and in similar trades, the purpose 5 thereof being to provide a device of this character whereby cloth may be readily wound or unwound from the bolt or roll in which it is ordinarily sold and laid upon a table preparatory to cutting the garment or other article 10 to be produced therefrom. This device is readily applicable either in connection with the cutting of patterns or a plurality of pieces from which a garment or other article is formed are cut out at a single time from the 15 pile of cloth thus accumulated or it may be satisfactorily employed in connection with the unrolling thereof for measuring.

One of the principal objects of my invention is to provide a cloth rolling or unrolling 20 device of this type which would be extremely simple in construction, easy to operate, and due to its novel construction may be readily placed into various operative positions. The scope of my invention extends to whatever 25 constructions may be defined by or included within the terms or language of the appended claims.

In the drawings:

Figure 1 is a side elevation of my device 30 shown as mounted vertically to a portion of a table, the dotted lines illustrating it in another position.

Figure 2 is a similar view partially broken away illustrating my device in a horizontal 35 position.

Figure 3 is a fragmentary view in perspective showing the cloth guiding means.

Figure 4 is an enlarged side elevation partially illustrated in section showing the bolt 40 reel.

Figure 5 is a front view thereof.

Figure 6 is a top plan view of the assembled device.

Figure 7 is a view in perspective of portions 45 of the bolt reel partially broken away and illustrated in their separated position, and

Figure 8 is a transverse sectional view of the usual bolt receiving board and the guide members forming a part of my invention.

50 My invention in the form or embodiment

shown in the drawings and briefly described comprises a stationary support A, a movably mounted bolt reel B and cloth guiding means C. Referring now particularly to Figure 1 in the accompanying drawings, the clamp 9 is 55 adapted to be secured to the table 10 in any desired manner and is provided with an extension 11 through which is formed a bore for the reception of the vertically extending support 12. This support 12 is preferably in the form of a tube or pipe and is provided on its upper end with an integrally formed collar 13 through which is threaded a set screw 14.

Mounted upon the supporting tube 12 is 60 a pair of sleeve members 15 each having a horizontally extending and integrally formed tubular extension 16. Wing nuts 17 are threaded through these extensions 16 near the outer ends thereof. I also thread wing nuts 18 through the sleeves 15 for the purpose of securely holding them at any desired position along the length of the supports 12.

Referring now particularly to Figures 4, 5, 7 and 8 wherein is illustrated the bolt 70 supporting means associated with my invention, I provide a pair of similarly formed ends indicated generally as at 19 which serve the purpose of a support for the bolt of cloth. Each of these ends is constructed of a substantially rectangular plate of metal 20 75 whose center is provided with a rectangular opening 21. A pair of outwardly extending angular ribs 22 are integrally formed with each plate 20 for the purpose of housing the U-shaped members 23 to which they are suitably riveted as indicated at 24. This construction it will be readily seen forms a housing or pocket for the reception of the ends of the board 25 and its associated guide strips 26.

One end of these guide strips 26 it will 80 be noted is riveted to the connecting strips or bars 27 as shown as at 28 whereas the opposite end of these strips 26 is provided with a recessed or notched portion 29 for a purpose to be described.

Openings 30 are transversely drilled 85 through the connecting strips preferably at a point between each pair of rivets 28 and are adapted to align with like openings formed through the angular extensions 22 and their 90

respective U-shaped members 23 for the reception of the wing bolts 31. It is obvious that when the board 25 together with its associated guide strips 26 is placed in its proper position within the pockets or openings 21, the wing bolts 31 may be inserted in their proper position and clamped or secured through the medium of the nuts 32. It will also be readily understood that since the 5 guide strips 26 are formed of relatively thin material they may be easily inserted between the board 25 and the bolt of material despite the fact that the cloth is usually tightly wound around the board 25. In practice I insert one pair of strips 26 together with its 10 mating connecting strip or bars 27 through each end of the bolt of cloth until the ends are on the same plane or until the openings 30 of one pair are in alignment with the 15 notches or recesses 29 of the opposite pair at which time the bolts 31 are inserted and readily clamped in their proper position. To separate each pair of strips from its position with respect to the board 25 it is merely 20 necessary to loosen the wing bolt 31 whereupon the strips may be slipped outwardly by reason of the notches 29.

On the outer end of each of the U-shaped members 23 I mount a stub shaft or member 33 which is preferably secured thereto by 25 means of screws. This member indicated generally as at 33 is provided with a substantially cylindrical portion 34 having a flared end 35 and a pair of lugs or ears 36 by 30 means of which it is secured to the U-shaped member 23. Each of these members 33 is further provided with outwardly extending 35 reduced and threaded portions 37.

Enlarged heads or bearings 39 are provided 40 with reduced shank portions 40 which are adapted to snugly fit within the outer ends of the tubular extensions 16, each being provided with suitable aligning openings for the reception of the wing bolt 17. Each of these 45 enlarged heads is further provided with a cylindrical bore or opening 41 for the reception of the end 33 and flared portions for the reception of the bolt bearings 42 as clearly indicated in the upper end of Figure 4.

50 These bolt bearings 42 are retained in their proper position by means of the nut 43 and the lock nut 44 which in turn are threaded upon the reduced threaded portion 37 of the member 33.

55 The cloth guiding means C is supported from the enlarged head 39 and may be secured to it in various positions depending upon the use of my device. As clearly indicated in Figures 1, 3, and 8, the cloth guiding 60 means consists of a pair of supporting strips 45 and 46, each being provided with angularly bent foot portions 47 which are provided with openings for the reception of screws 48, the supporting strips 45 and 46 being secured to the enlarged heads 39.

The supporting strip 45 is provided with an angularly bent portion and terminates in an enlarged end for the purpose of providing a hinged portion 49. A pin is passed through this enlarged hinged portion and is 70 adapted to pivotally mount the enlarged heads 50 of the pair of rods 51 which it will be noted from Figures 1 and 3 serve the purpose of mounting the rollers 52. The free ends of the rods 51 are provided with cut-away portions for the purpose of engaging with similarly formed portions 53 which are oppositely disposed with respect to the rods 51 and are integrally secured to the supporting bar or arm 46. A lug or latch 54 is slidably mounted upon the stub shafts and is adapted to lock the rods 51 when they are in their closed position as shown in Figure 1. A leaf spring 55 is carried by the latch 54 and is provided with an off-set portion arranged 80 to engage the end of the supporting arm 46 to maintain it in its locked position.

Referring now to Figure 2 I illustrate an angular brace 56 for the purpose of supporting one end of the reel. In this instance the brace is provided with a horizontally bent end which is adapted to engage the tubular portion 16 of the support and is provided at its other end with an enlarged tubular end 57 for the purpose of supporting the extension 40 of the enlarged head 39. It will be obvious that this brace will be made sufficiently strong to support the desired weight of the roll of material. Then too it may be found desirable to employ another 90 vertical support 12 at this free end.

Since my improved reel is mounted upon ball bearings, it is obvious that it will rotate and operate very freely, which rotation may be accomplished by means of a belt drive 105 from a motor not shown or it may be manipulated by hand. When a belt drive is employed the belt merely passes around the pulley 58 which it will be noted from Figure 4 is screwed upon the threaded end 37. The pulley is also provided with an outwardly extending polygonal end 59 to receive one end of crank 60 as shown in Figure 2.

It may be here stated that the cloth guiding means C may be supported or secured 115 to the enlarged heads 39 from any one of three positions, depending upon the wishes of the operator.

Having thus described my invention, I claim:

1. A device for winding and unwinding cloth around a cloth board, comprising a vertically disposed supporting rod having a bore in its upper end thereof, a detachably mounted and laterally extending arm carried by the 125 supporting rod having a bore in its free end, a headed bearing member provided with a laterally extending and reduced shank portion adapted to be detachably secured, either, within the bore in said supporting arm or 130

the bore in the free end of said laterally extending arm, and a bolt reel revolvably mounted within said headed bearing member.

5 2. A device for winding and unwinding cloth around a cloth board, comprising a vertically disposed supporting rod, a detachably mounted and laterally extending arm carried by the supporting rod, a headed bearing member, means for detachably securing said headed bearing member to either the upper end of said rod or to the free end of said laterally extending arm, and a bolt reel revolvably mounted within said headed bearing member.

10 3. A device for winding and unwinding cloth around a cloth board, comprising a pair of relatively thin and spaced guide strips disposed to overlie one side of the cloth board, a transversely extending bar rigidly connecting the guide strips at one end thereof, the opposite end of said guide strips having recesses for detachable connection with its adjacent end support, and a pair of 15 similarly formed end supports each having a substantially rectangular recess therein for the reception of the ends of the cloth board and the respective ends of said guide strips.

MOSES SCHNEIDER.
